FIG. 1.

FIG. 2.

FIG. 3.

INVENTOR.

HERBERT L. ROSS

BY *Baedeker, Inc.*
ATTORNEYS.

UNITED STATES PATENT OFFICE

HERBERT L. ROSS, OF OAKLAND, CALIFORNIA

KNIFE

Application filed June 30, 1931. Serial No. 547,925.

This invention relates to improvements in knives and more particularly to sheath handles for razor blades.

The principal object of the invention is to provide means for safely utilizing the wafer type of razor blade for a cutting and ripping knife.

Another object is to provide a safety sheath for the blade when not in use.

10 Other objects and advantages will appear as the description progresses.

In this specification and the accompanying drawings the invention is disclosed in its preferred form. It is to be understood, however, 15 that it is not limited to this form because it may be embodied in other forms within the purview of the claims following the description.

In the one sheet of drawings:

20 Fig. 1 is a side elevation of a knife constructed in accordance with this invention.

Fig. 2 is a longitudinal section of the same taken on the line II—II, Fig. 1.

Fig. 3 is a detached detail view in longitudinal section of the blade holder.

In detail the construction illustrated in the drawings comprises the blade holder preferably composed of a single strip of sheet metal such as steel, hard brass, or the like. It is 30 bent back upon itself at 1 to form the parallel sides 2—3, substantially as shown in Fig. 3.

The side 2 is perforated at 4—5, to register with the tits 6—7 struck up from the body of the side 3. These tits are arranged to pass 35 through the perforations in the conventional two-edged razor blade X of the "Gillette" type.

The ends of the holder sides 2—3 may be 40 varied in any suitable manner to grip other forms of wafer blades, now available, some of which have end notches, and other distinguishing perforations, like the "Valet" and others. It is within the ability of any skilled mechanic to adapt the present invention to various forms of blades. The ends of 45 the holder are beveled as at 8, Fig. 1, to expose about one half the length and width of the blade X for cutting purposes. The end of the side 2 is flanged over at 9, to enclose 50 the end 10 of the side 3 and the end of the

blade X to take the thrust when the cutting edge 11 is used, working in conjunction with the tits 6—7 to aline the blade X and hold it rigidly when in use.

With the blade in place the sides 2—3 of the holder are compressed together and inserted into the end of the sheath-handle.

This handle comprises a single strip of sheet metal folded back upon itself at 12—13 intermediate its width to form the back 14 and the front composed of the margins 15—16 adjacent the edges 17—18. The bends at 12—13 should be of sufficient radius to give a comfortable bead, such as at 1, for the hand of the operator. These edges 12—13 and 1 may be knurled to insure a good frictional hold in manipulating the knife.

The margins 15—16 are cut away in any suitable pattern to form the resilient detents 19—19, 20—20, properly shaped to frictionally engage the tits 6—7. In the operative position as in Fig. 1, the holder is pushed through the handle until the tit 6 engages the detents 20—20 which effectively lock the blade in cutting position. The sheath the 75 blade the end flange 9 can be tapped on a counter or pushed against any surface, to overcome the resilient resistance of the detents 20—20, which will permit the tit 6 to retreat to a similar frictional engagement 80 with the detents 19—19, which holds the blade in the retracted position telescoped within the sheath-handle.

The blade may be advanced to the operative position by similarly tapping the end 1 of the holder, or the blade holder may be advanced or retracted by firmly grasping the handle in one hand and pushing or pulling the blade holder with the other. For a better grip upon the holder at 1, the margins 15—16 90 are cut away at 21—21 to expose more gripping surface on the holder. The holder has the hole 22 for convenience in hanging up the knife or attaching it to a key chain.

In its present proportions, approximately 95 full size, the knife is especially adaptable for opening fiber board packing cases and other rough work. Smaller sizes can be made by shortening the handle, for ordinary work.

The blades may be reversed or replaced in 100

an obvious manner. If the larger radius is reduced to a simple fold at 1, that end may be inserted into the front end of the sheath in assembling the device.

- 8 The detents 19—20 could be dispensed with and the holder held firmly within the sheath-handle by the frictional clamping action of the margins 15—16 which are resilient at the folds 12—13. The end 1 will prevent the 10 holder pulling out of the handle when in use, see Fig. 1.

Having thus described this invention what is claimed and desired to secure by Letters Patent is:

- 15 1. A knife including a sheath composed of a strip of sheet material folded back upon itself with two of its edges in proximity and provided with resilient detents, a blade holder slidable in said sheath and composed of a 20 piece of sheet material folded back upon itself, a tit on one of the sides of said holder projecting through holes in the opposite side and engageable with said detents, and a blade in said holder engaging said tit.
- 25 2. A knife including a handle composed of a strip of sheet material folded back upon itself with two of its edges in proximity and forming a sheath, resilient detents formed in the adjacent edges of said folded-over 30 sheath handle, a blade holder slidable in said sheath and composed of a piece of sheet material folded back upon itself forming a transverse resilient hinge, a tit on one of the sides of said holder projecting through a hole 35 on the opposite side and adapted to engage said detents, and a blade between the two sides of said holder and engaging said tit.
3. A knife including a sheath provided with resilient detents, a blade holder slideable in said sheath and composed of a piece of sheet 40 material folded back upon itself forming a transverse resilient hinge, a tit on said holder engageable with said detents, a blade in said holder and engaging said tit, 45 and a depending flange on the end of one of the sides of said holder opposite said resilient hinge and adapted to engage and align said blade.
4. A knife including a sheath provided with 50 resilient detents, a blade holder slideable in said sheath and composed of a strip of sheet metal folded back upon itself forming a transverse resilient hinge, a tit on said holder engageable with said detents, and a blade be- 55 tween the folded over portions of said holder and engaging said tit.

In testimony whereof I have hereunto set my hand this 25th day of June, 1931.
HERBERT L. ROSS.
